ALBERT H. STEBBINS, OF LOS ANGELES, CALIFORNIA.

SCREEN.

Application filed March 3, 1926. Serial No. 91,928.

This invention relates to screens and more particularly to a simple construction for preventing clogging of the screening slots or apertures.

5 The tendency of ordinary apertured screens to become clogged while in use seriously interferes with their proper operation; and various forms of operating means have been proposed heretofore that are designed to shake or vibrate the screening surface with sufficient force to throw the particles that lodge in the apertures out of the same.

10 These devices for shaking a screening surface with sufficient force to dislodge the clogging particles are open to the objection that they subject the screening surface to severe stresses that tend to wear it out rapidly, and they may also seriously disturb the proper sifting or screening operation.

15 The present invention is therefore directed to a screen the screening surface of which is so constructed that the particles that lodge in a slot may readily escape therefrom by traveling lengthwise of the slot until they escape from the end thereof.

20 One important feature of the present invention resides in a screening surface that is provided with a series of screening slots each of which increases in width in the direction in which the materials travel, and as a result of this construction the larger particles that lodge in a slot readily work lengthwise of the same in the direction in which its width increases to escape from the end of the slot.

25 Another feature of the invention resides in the construction whereby the sections of the screening surface are disposed in overlapping relation so that the materials that travel lengthwise of a slot may readily escape from the end thereof without escaping from the screening surface.

30 Other features of the invention and novel combination of parts in addition to the above will be hereinafter described in connection with the accompanying drawings which illustrate one good practical form of the invention.

35 In the drawings:—

Fig. 1 is a top plan view of a screen constructed in accordance with the present invention.

40 Fig. 2 is a side elevation of the screen

of Fig. 1 shown mounted upon a supporting frame, parts of the screen casing being broken away to show the material supporting surface.

Fig. 3 on an enlarged scale is a sectional perspective view of a portion of the screen of Fig. 1.

Fig. 4 is an enlarged sectional view taken on the line 4—4 of Fig. 1; and

Fig. 5 is a top plan view of one of the ribs to be described.

The casing which is provided with the material supporting surface may be given any suitable shape or size, and the same may be mounted upon a frame for back and forth movement, as shown in Fig. 2 of the drawing, or if desired it may be supported at a relatively steep inclination in the direction of its length so that the materials being treated will flow over the screening surface under the influence of gravity without requiring the surface to be vibrated.

The screening casing shown in the drawings is provided with a floor 10 upon which the finer materials fall upon passing through the screening surface. At the opposite sides of the material treating casing are provided the side walls 11 to which the floor 10 may be secured, and the material treating casing in the present case is shown as rectangular in shape and as having the feed hopper 12 at the left-hand end thereof. The rate at which the materials flow from the feed hopper 12 may be regulated as desired by adjusting the sliding gate 13. In order to strengthen the casing and impart the desired stiffness to the same the floor 10 and side plates 11 may be secured to the channel irons 14 mounted at the opposite sides of the casing. These channel irons serve to support the material supporting surface to be described, and if desired one or more additional channel irons 15 may be provided within the casing in spaced relation to the side channels 14, as best shown in Figs. 3 and 4.

If the screen is to be vibrated to promote travel of the materials lengthwise of the same the screening surface may be supported by any suitable means for back and forth movement in the direction of its length. In the construction shown in Fig. 2 the screening casing is supported at an inclination in the direction of its length by a frame formed of the uprights 16 to which

are secured the side rails 17, and it should be noted that this frame is higher at its left-hand end than it is at its right-hand end, to impart the desired slope to the screen 5 mounted thereupon. The means shown for supporting the screen casing for back and forth movement consists of bearing blocks 18 mounted upon the supporting frame and in each block 18 is mounted a ball or roller 10 19 the upper portion of which enters a correspondingly shaped bearing block 20 secured to the channel irons 14 of the material treating casing.

The supporting casing may be moved back 15 and forth with a simple reciprocatory movement, or with a progressive vibratory movement, as may be desired, and the means shown for imparting a vibratory movement to the screening casing consists of a cable 20 21 an intermediate portion of which is rigidly secured to the casing by clamping means or the like 22. The portion of the cable 21 extending from the clamping means 22 in the right-hand direction extends about a grooved 25 sheave 23 which sheave is rotatably supported by a shaft 24 that is supported by bearing brackets 25 secured to the supporting frame. The portion of the cable 21 that extends downwardly from the grooved sheave 23 is 30 conveniently secured to a pipe or hollow tube 26 the lower end of which is threaded, and the pipe or tube 26 is yieldingly secured to the supporting frame. To this end a coiled spring 27 is confined between a transversely 35 extending beam 28 secured to the supporting frame, and adjustable nuts 29 secured to the threaded lower end of the tube 26. The arrangement is such that the spring 27 will exert a continuous pull upon the cable 21 40 that tends to move the screen casing in a right-hand direction, and the tension of the spring 27 may be adjusted as desired by adjusting the nuts 29 upon the tube 26. The means shown for alternately pulling the screen casing in a left-hand direction and then releasing it consists of a grooved sheave 30 about which is looped that portion of the cable 21 which extends in a left-hand direction from the securing means 50 22, and the end portion of this cable extends from the lower face of the sheave 30 to anchoring means 31 which may be adjustably secured to a transversely extending beam 32 of the frame. The sheave 30 is 55 mounted upon an eccentric 33 which is rigidly secured to the driving shaft 34, and this shaft may be journaled in the bearing brackets 35 that are secured to the supporting frame. 60 The operating shaft 34 may be driven by a pulley or other means (not shown) and as this shaft rotates it turns the eccentric 33 within the sheave 30 to move the latter back and forth towards and from the cable 65 tightening position to thereby pull the screen

casing in a left-hand direction and then release it to move in a right-hand direction under the pull of the tensioned spring 27.

The construction so far described forms no essential part of the present invention, 70 but is shown and described to make clear the construction and operation of the material supporting surface which will now be described. This material supporting surface in the construction shown is formed of 75 a number of ribs 36 and these ribs are preferably mounted side by side to form the sections 37, and the entire screen supporting surface is made of any desired number of 80 the sections 37 disposed lengthwise of the casing in overlapping relation to each other; that is, the discharge end 38 of one section is disposed above and overlaps the leading end 39 of the next section. The sections 37 are preferably so disposed that the 85 ribs of the successive sections lie in alignment with each other lengthwise of the casing so that a valley extending lengthwise of the casing is formed between adjacent pairs of ribs. The ribs 36 may be formed of sheet 90 metal, cast iron or other material as desired, and these ribs are preferably somewhat V-shaped in cross section as shown, the construction being such that each rib is provided with oppositely sloping sides which will direct the materials resting upon the ribs into the valley formed between a pair of ribs. 95

The screening of the materials being treated is effected by providing the screening surface with the slots 40 the size of which may be as large or as small as desired to accommodate the particular screening operation to be effected. The fine particles which pass through the slots 40 fall upon the floor 10 of the casing and slide along the same 100 towards the right-hand end of the casing until they enter the discharge hopper 41 provided for these materials. The coarse materials which are unable to pass through the slots 40 will travel lengthwise of the screening surface over the successive sections 110 37 until they finally reach the discharge hopper 42 for the coarse materials.

Each slot 40 is preferably constructed so 115 that its width gradually increases in the direction in which the materials flow. This is desirable because the increasing width of the slots reduces the tendency of the larger particles to become stuck or wedged in the slots. Since the sections 37 are disposed in 120 overlapping relation to each other, and the slots 40 increase in the direction of their length, the materials that lodge in a slot 40 will readily move lengthwise of the same until they are able to pass through the wider portion of the slot 40, or until they escape from the open end of the slot to fall upon the next section 37.

In the construction shown the slots 40 are formed by providing each rib 36 with 125

the tapered side portions 43, as best shown in Fig. 5, and these tapered side portions preferably terminate a short distance from the wider end of the rib to form the portion 44 adapted to abut against a similar portion of the adjacent rib to thereby properly position the various ribs of a section 37, as will be apparent from the drawings.

In the construction shown the ribs 36 are secured to and are supported by the transversely extending beams 45 that rest upon the channel irons 14 and 15, and as stated each rib 36 is supported so that it slopes upwardly in the direction of its length. To this end the wide portion 44 at the leading end of a rib may rest upon a supporting beam 45, while the discharge end of the same rib is supported in spaced relation to the next transversely extending beam 45. A block 46 may be positioned between the leading end of each rib and its supporting beam, while at the opposite or discharge end of each rib is provided a second block 47 which serves to space this end of the rib a substantial distance from the rib it overlaps, as will be apparent from the drawing. The various ribs may be clamped in their overlapping relation by bolts 48 extending through holes 49 formed in the ribs and through the supporting blocks 46 and 47 and beam 45, and each bolt 48 is secured in place by a nut 50. Each block 47 it should be noted has its lower end shaped to fit the V-shaped rib upon which it rests and the upper end of each block 47 is shaped to fit the inner face of the rib it supports. As a result of this construction the overlapping ribs are held in alignment one above the other and are properly spaced laterally from each other.

The blocks 47 should support the discharge end of a section 37 a sufficient distance above the leading end of the next section to prevent any particles such as α (see Fig. 4) that extend downwardly a substantial distance through a slot from striking against the leading end 39 of the next section. This is important because if the particles α which extend downwardly within the slots 40 are permitted to engage the leading end 39 of a rib or section, their movement in the slot will be arrested, thus causing clogging of the screen.

From the foregoing description, when read in connection with the drawings, it will be seen that the screening surface forming the subject matter of the present invention is so constructed that the particles which lodge within the slots 40 may readily travel lengthwise of the slots until they escape from the ends thereof, whereupon they fall upon the next section of the screen to travel along the same for further treatment. In this manner the particles which are too large to pass through a slot 40 are

prevented from becoming wedged therein to interfere with the proper operation of the screen.

The novel construction forming the subject matter of the present invention not only prevents clogging, but also facilitates the use of a screen of maximum length, since the large particles that enter a slot will not remain in the slot throughout the entire length of the screen, but will escape therefrom upon reaching the end of a section. Furthermore, the present construction may readily be given sufficient strength to stand up under coarse, heavy work, and if a rib becomes worn or broken it may readily be removed and replaced by a new rib.

What is claimed is:—

1. A screen for separating materials, comprising in combination, a casing having a material supporting surface formed of a multiplicity of separate ribs each having the shape of an inverted trough, means for supporting the ribs in rows extending lengthwise of the casing with their ends in overlapping relation, including spacer blocks having their lower ends shaped to conform to the curved face of the ribs upon which they rest and their upper ends shaped to conform to the curved inner face of the ribs they support to thereby align the overlapping ribs, and flanges formed at the block supporting end of each rib for spacing the ribs laterally from each other to form slots between them.

2. A screen for separating materials, comprising in combination, a casing having a material supporting surface formed of a multiplicity of separate ribs each having a longitudinally extending ridge, means for supporting the ribs in rows extending lengthwise of the casing with their ends in overlapping relation, including spacer blocks mounted between the overlapping ends of the ribs and each rib having its lower face constructed to fit a ridge and thereby align one rib over the other, and flanges formed at the block supporting end of each rib for spacing the ribs laterally from each other to form slots between them.

3. A screen for separating materials, comprising in combination, a casing having a screening surface formed of a multiplicity of separate ribs having downwardly sloping sides, means for supporting the ribs in rows extending lengthwise of the casing with their ends in overlapping relation, including spacer blocks between the overlapping ends of the ribs and each block having its lower end shaped to fit the downwardly sloping sides of the rib upon which it rests to thereby centre one rib over the other, and flanges between the ribs at the block supporting end of each rib for spacing the ribs laterally from each other to form slots between them.

4. A screen for separating materials, com-

prising in combination, a casing having a screening surface formed of a multiplicity of ribs having downwardly sloping sides and spaced laterally to form slots between them, 6 means for supporting the ribs in rows extending lengthwise of the casing with their ends in overlapping relation, and including spacer blocks between the overlapping ends of the ribs and each block having its lower 10 end shaped to fit the sloping sides of the rib upon which it rests to thereby centre one rib over the other.

5. A screen for separating materials, comprising in combination, a casing having a 15 screening surface formed of a multiplicity

of ribs provided with faces that slope laterally from a central ridge, means adjacent the material receiving end of each rib for spacing the ribs laterally apart to form slots between them, means for supporting the ribs in rows extending lengthwise of the casing with their ends in overlapping relation, and including spacer blocks between the overlapping ends of the ribs and having their lower faces constructed to fit the laterally 20 sloping faces of the ribs to thereby insure centering of one rib over the other. 25

In testimony whereof, I have signed my name to this specification.

ALBERT H. STEBBINS.
